his Attorneys.

UNITED STATES PATENT OFFICE.

JAMES R. ARMINGTON, OF ALLSTON, MASSACHUSETTS, ASSIGNOR TO DENNISON MANUFACTURING COMPANY, OF FRAMINGHAM, MASSACHUSETTS, A CORPORATION OF MASSACHUSETTS; WHICH COMPANY HAS DEDICATED ENTIRE RIGHT TO THE PEOPLE OF THE UNITED STATES OF AMERICA.

SURGICAL BANDAGE.

1,263,728.

Specification of Letters Patent. Patented Apr. 23, 1918.

Application filed January 12, 1918. Serial No. 211,640.

To all whom it may concern:

Be it known that I, JAMES R. ARMINGTON, a citizen of the United States of America, and resident of Allston, in the county of 5 Suffolk and State of Massachusetts, have invented new and useful Improvements in Surgical Bandages, of which the following is a specification.

This invention relates to surgical dressings and more particularly to surgical bandaging material.

The principal objects of the invention are to provide a bandaging material which is soft yet comparatively strong, which will 15 absorb liquids rapidly and in large quantities, which is exceedingly yielding and to some extent elastic, and which possesses other characteristics peculiarly adapting it to surgical dressings.

20 I attain the aforesaid objects by making my improved bandages of absorbent paper or other bibulous material adapted to be given a peculiar formation which will permit a given length of bandage to absorb a relatively large amount of liquid, and which renders the bandage yielding and elastic when dry so that it may be closely applied to an injured member without binding the member too tightly. The peculiar formation 25 of the bibulous material of the character referred to is characterized by inequalities which may comprise a series of raised portions or alternate raised and depressed portions which may be regularly or irregularly arranged. The formation may comprise a series of regular waves or corrugations or a plurality of irregular ridges or projections, and the inequalities may be formed either by crinkling, rumpling, wrinkling, 30 folding, creasing, corrugating, crimping or in other suitable manner.

In the accompanying drawings,—

Figure 1 is a perspective view of a roll of my improved bandage material; and 45 Fig. 2 is a longitudinal section through the material.

The particular embodiment of my invention chosen for the purpose of illustration comprises a roll A of bibulous paper of suitable width to be employed as bandage material. The paper has a series of crinkles, 50 crimps or corrugations extending transversely thereof as indicated at B in the fig-

ures, thereby to produce a rimose or rimulose surface on both sides of the paper the 55 clefts and crevices of which are fairly deep. The crinkles are preferably formed close together, fifty to seventy-five to the inch for example, and fairly deep, the material being reduced in length about fifty per cent. 60 by the crinkles, so that the walls of the crevices are relatively close together. By subjecting the bandage to a relatively strong lengthwise pull the crinkles or corrugations may be stretched out as indicated at C in 65 Fig. 1.

The paper which I prefer to employ in my improved bandages is made of wood pulp with the fibers extending predominantly in the direction of the length of the bandage, 70 thereby affording a material which is relatively open and porous but which nevertheless has a relatively high tensile strength.

A bandage of the character herein disclosed possesses many advantages of which 75 the principal advantages are the following: By virtue of the crinkles or inequalities in the material a relatively long length of material is compressed into a relatively short length of bandage so that a given length of 80 bandage will absorb a much greater amount of liquid than would a flat bandage. The corrugations or wrinkles not only make the bandage exceedingly yielding so that it may be readily applied and adapted to a 85 member of any shape or contour but they also make the bandage moderately elastic so that the turns or windings will tend to contract sufficiently to hold the bandage in position but not to such extent as unduly to 90 squeeze the member to which the bandage is applied. Moreover, when the bandage is wound fairly loosely around a member the crinkles prevent the windings from being 95 tightly compressed together and thereby permit ventilation and freedom of movement, whereas if the bandage is wound tightly around a member the crinkles are stretched out so that the windings are compressed tightly together as in the case of an ordinary bandage.

By arranging the fibers of the paper predominantly lengthwise of the bandages a maximum strength for a given degree of softness and porosity may be obtained. 105 Moreover, the elasticity of the bandage is in-

creased by arranging the fibers longitudinally and at the same time forming the crinkles transversely inasmuch as the crinkles then extend transversely of the fibers.

5 Thus it appears that additional advantages are obtained either by arranging the fibers longitudinally or by forming the crinkles transversely and that still further advantages are afforded by utilizing both of 10 these two features together, but it will be understood that certain of the objects of the present invention are attained when the fibers are not arranged longitudinally, when

the crinkles are not formed transversely, and when neither of these features are employed. 15

I claim:

1. A surgical bandage comprising a ribbon of bibulous material having crinkles extending crosswise thereof.

2. A surgical bandage comprising a ribbon of bibulous paper having transverse crinkles extending the full width thereof. 20

Signed by me at Framingham, Massachusetts, this ninth day of January, 1918.

JAMES R. ARMINGTON.
